US00D631048S

(12) **United States Design Patent**
Adriano et al.

(10) **Patent No.:** US D631,048 S
(45) **Date of Patent:** ** Jan. 18, 2011

(54) **COMPUTER KEYBOARD**

(75) Inventors: **Gabriele Adriano**, Turin (IT); **Davide Adriano**, Turin (IT)

(73) Assignee: **Progind S.R.L.**, Strada Tomboleto (IT)

(**) Term: **14 Years**

(21) Appl. No.: **29/336,855**

(22) Filed: **May 11, 2009**

(30) **Foreign Application Priority Data**

Nov. 12, 2008 (EM) 1037626

(51) **LOC (9) Cl.** **14-02**

(52) **U.S. Cl.** **D14/399**

(58) **Field of Classification Search** D14/387-401,
D14/356, 346, 432, 454-457, 217, 218; D21/324,
D21/333; D18/7, 12.2; D19/60; 341/22-28;
463/37; 345/168, 169
